UNITED STATES PATENT OFFICE.

KURT ARMAND DIEKELMANN, OF BIRMINGHAM, ALABAMA.

WARDROBE TRUNK.

Application filed May 5, 1925. Serial No. 28,210.

To all whom it may concern:

Be it known that KURT ARMAND DIEKELMANN, a citizen of the United States, residing at Hotel Tutwiler, Birmingham, in the county of Jefferson and State of Alabama, has invented certain new and useful Improvements in Wardrobe Trunks, of which the following is a specification.

This invention relates to improvements in 10 wardrobe trunks of a nature adapted to constitute an invisible wardrobe by utilizing the space under a bed in hotels, apartments, hospitals, clubs and homes. This device is of great utility since it utilizes space otherwise wasted. By the use of this device, built 15 in closets may be eliminated in small rooms with a consequent marked economy in space and with the elimination of the very considerable cost of installing built-in wardrobes or closets, in buildings of the character 20 above indicated.

Further objects and advantages of the invention will be set forth in the detailed description which follows.

25 In the accompanying drawings:

Fig. 1 is a perspective view of a wardrobe trunk constructed in accordance with the invention.

Fig. 2 is a longitudinal vertical sectional 30 view therethrough.

Fig. 3 is a transverse vertical sectional view.

Fig. 4 is a fragmentary vertical sectional view illustrating an operating mechanism 35 hereinafter described.

Fig. 5 is a detail perspective view illustrating the mounting of a swinging panel hereinafter described, and

Fig. 6 is a horizontal sectional view 40 through the structure of Fig. 5.

Like numerals designate corresponding parts in all of the figures of the drawings.

Referring to the drawing, 5 designates a box-like body portion that is provided with 45 a top 6. This top is hingedly connected to the body 5, at 7, and is adapted to be held in raised position by a sliding brace 8 of the usual and well known type. A panel 9 is mounted to be swung from the full line position illustrated in Fig. 2 to the dotted line position of said figure. This panel is secured to and moves with a rod of inverted U shape indicated at 10. The lower ends of the rod 10 are out-turned as indicated at 10^a 50 in Fig. 5 to constitute pintles upon which the rod and panel pivot. Panel 9 is held

to the rod 10 by rivets indicated at 11. The panel 9 constitutes a support for a rod 12. This rod carries a washer 13 which bears against the panel 9 and the rod 12 passes through the panel and through the rod 10 and is provided with a rubber cushioning element 14 rearwardly of said rod 10. A handle 15 upon the outer or free end of the rod 12 provides the means by which the panel may be swung to the position illustrated in Fig. 1, or by which said panel, together with garment carrying clothes hangers, 16, may be lowered into the body 5. The cushioning element 14 provides means for absorbing shock if the panel, with its load, be dropped roughly into place.

A cushioning stop 17, upon the end wall of the body 5, provides means for limiting the upward swinging movement of the panel 9 and it will be observed that the pivot point 18 of the panel is such, with respect to the stop 17, that the panel and its associated parts may move to a position slightly beyond the vertical. It will be further observed by referring to Fig. 2 that the rod 12 lies at a slight inclination with respect to the panel. The result is that the panel will stand erect without the use of extraneous devices.

According to the structure illustrated in Fig. 2 the device is to be operated by hand. However I contemplate employing means for operating it by foot power, said means being illustrated in Fig. 4. In this figure 10^b designates a spindle corresponding to the spindle 10^a of Fig. 5. A pinion 19, mounted upon said spindle, is connected with a segmental gear 20, the shaft 21 of 95 which carries a foot operated lever 22, the latter lying outside of the body 5^a. By pressing downwardly upon the foot lever, the pinion 19 will be turned to actuate the spindle 10^b and thereby swing the rod of 100 inverted U shape, together with the panel, to vertical position, it being understood that the panel and associated parts will be the same in Fig. 4 as in the other figures the only difference being that the spindle of the 105 rod of inverted U shape will carry a pinion for engagement with the segmental gear, as described.

Elongated straight rollers 23 are secured to the undersides of the body 5, 5^a and are 110 of such a nature as to impart a straight line movement to the structure in the direction

of its length, when it is drawn upon by engagement of a handle 24. Thus the structure may readily be pushed back beneath a bed or withdrawn from beneath a bed as required.

When the top is opened, garments, mounted upon hangers, are presented in such way that the owner may select any desired garment without disturbing the others. In like manner, any garment may be put away without disturbing the remaining garments, and any garment may be put away in any desired order, i. e., it may be placed in such position that it will be on the top or bottom of the pile, or at any intervening point with respect thereto, when the panel is lowered into the body 5. It is apparent that many ways will suggest themselves of mounting the panel for vertical swinging movement into and out of the body 5 and I wish it to be understood that the invention is not limited to the precise construction set forth but that it includes within its purview whatever changes fairly come within either the terms or the spirit of the appended claims.

Having described my invention, what I claim is:

1. In a device of the character described, in combination with a body portion and a cover for the same, of a panel extending transversely of the body portion and hingedly connected thereto at a point adjacent to the bottom of the body portion, a hanger supporting rod extending from the panel at a point adjacent the top and manually operable means operative from the exterior of the body portion for swinging said panel from a position where it lies substantially within the body to a position where it lies substantially vertical to the body.

2. In a device of the character described, in combination with a body portion and a cover for the same, of a rod of substantially

inverted U shape, having out-turned lower ends, constituting a pivot, means for hingedly connecting said pivot to the body, a panel secured to the said rod, a hanger carrying rod traversing the panel and the U shaped rod and carrying a rubber cushioning element rearwardly thereof, said hanger carrying rod being slightly inclined with respect to the panel.

3. A device of the character described comprising a body portion and a cover for the same, an elongated panel hinged within the body portion adjacent one end thereof and close to the bottom thereof, a hanger supporting rod extending at substantially right angles from the panel, at a point adjacent the top thereof, a manually operable lever upon the exterior of the body portion and gearing between the lever and the hinged mounting of the panel of such a nature that a small degree of movement of the lever imparts a greater degree of movement to the panel to swing the same to elevated position, where it lies substantially vertical to the body.

4. A device of the character described comprising a body portion, a cover for the same, a panel adapted to swing downwardly into the body portion and to lie along the bottom thereof, a hanger supporting element carried by the panel and projecting substantially at right angles thereto, a pivotal mounting for the panel, within the walls of the body portion, an operating lever upon the exterior of the body portion, a gear segment connected to move with the operating lever and a pinion carried by the pivotal mounting of the panel, said gear segment being of considerably greater radius than the pinion, as and for the purposes set forth.

In testimony whereof he affixes his signature.

KURT ARMAND DIEKELMANN.
